UNITED STATES PATENT OFFICE.

GEORGE A. STEINER, OF SALT LAKE CITY, UTAH, ASSIGNOR, BY MESNE ASSIGNMENTS, TO STEINER SALES COMPANY, OF SALT LAKE CITY, UTAH, A CORPORATION OF UTAH.

TOWEL CABINET.

Application filed February 21, 1921. Serial No. 446,915.

To all whom it may concern:

Be it known that I, GEORGE A. STEINER, a citizen of the United States, resident of Salt Lake City, county of Salt Lake, State of 5 Utah, have invented certain new and useful Improvements in Towel Cabinets, of which the following is a specification.

The object of my invention is to provide a towel cabinet comprising an upper portion 10 or superstructure which can be conveniently mounted on the top of a soiled towel container now in general use, thereby effecting a considerable saving in the cost of the cabinet.

15 A further object is to provide a cabinet adapted to receive a roll of toweling and from which the clean towel is delivered or unrolled without the aid of springs or other mechanism which add to the expense of construction and upkeep.

A further object is to provide a cabinet that is particularly adapted for the convenient insertion of the roll of clean towel and the removal of the soiled portion.

25 In the accompanying drawings forming part of this specification,

Figure 1 is a front elevation of a towel cabinet embodying my invention,

Figure 2 is a vertical sectional view of the 30 upper portion of the cabinet, showing the roll of towel mounted therein,

Figure 3 is a similar view, showing a slightly modified construction in the cabinet,

Figure 4 is a sectional view, showing a 35 modified arrangement of the roll guides,

Figure 5 is a similar view, showing still another arrangement of the guides.

In the drawing, 2 represents the base of the cabinet, having suitable supporting legs 40 3 and a front wall 4 in the rear of which is a compartment or chamber 5 that is adapted to receive the soiled towel from above. An opening 6 leads to this chamber or compartment and through this opening the user may

45 reach the towel and draw it forward where it can be conveniently used for wiping the hands or face. On the top of this base I arrange the cabinet proper, which consists of a box-like structure having a rear wall 7 and end walls 8 that are adapted to fit the 50 top of the base 2, a cover 9 being preferably provided for closing the top hinged to the rear wall at 10. The lower portion of the cabinet proper has a cross bar or floor 11 of 55 less width than the cabinet and separated

from the rear wall 7 by a gap or opening 12, the end walls of the cabinet having slots 13 therein and the towel roll 14 has a shaft 15 that is adapted to slide vertically in the guides 13 and hold the roll of toweling with- 60 in the cabinet while permitting it to be revolved to unwind the clean towel. The loose free end of the towel is dropped down through the gap 12 into the space beneath, where it can be reached by the user and drawn forward through the opening 6 to a point where it can be conveniently used for wiping. The roll of toweling rests by gravity upon the floor 11 and there will be 65 sufficient friction between the toweling and this floor to prevent the roll from unwinding too rapidly when a pull is applied to the loose end. There will be less weight on the bar 11, of course, as the towel is unwound, and a greater tendency for the roll to turn 70 prematurely.

In Figure 3 I have shown a modified construction which consists in providing guide slots 16 obliquely in the end walls of the cabinet so that the roll 14, instead of contacting with the floor 11, slides rearwardly 80 against the rear wall and when the loose end of the towel is pulled, the pressure of the roll against the rear wall is increased and the desired resistance is offered to the user of 85 the towel.

In Figure 4 I have shown an oblique guideway 16^a a little steeper in pitch than the guide 16 of Figure 3, so that the roll when well filled will bear against the rear 90 wall of the cabinet. The lower end of the guideway 16^b is offset slightly so that as the roll gets smaller, it will contact with the rear wall and with the floor 11, as indicated by dotted lines, the pull of the towel on the roll increasing the pressure on the floor 11 and retarding the unwinding of the roll.

In Figure 5 I have shown a guideway 16 arranged at an angle substantially of 45 degrees so that the roll of toweling will contact at all times with the rear wall and with the floor 11, resting by gravity thereon when the roll is first inserted into the cabinet and remaining in contact therewith as the towel is unwound. When the roll is entirely 100 unwound, the cover is raised and a fresh roll inserted in the guides. The accumulation of soiled toweling in the bottom of the receptacle is taken out and returned to the laundry, and the cabinet is then ready for 105 110

use again when a clean roll has been inserted.

I claim as my invention:

1. A towel cabinet comprising a casing having rear and end walls and guideways in said end walls and a floor near the lower ends of said guideways, a clean towel roll having a shaft adapted to fit and slide in said guideways and sail roll contacting with the rear wall of the cabinet during the initial unwinding of the toweling, the lower portion of said guideways having an offset section therein to receive said roll shaft when a considerable portion of the towel has been unrolled and direct the roll against said floor as well as the rear wall, and a gap being provided between said floor and rear wall through which the clean towel may be drawn by the user.
2. A towel cabinet comprising a casing having a delivery opening in its upper portion at the front of the cabinet, a transverse floor within said casing in the rear of said opening, a comparatively narrow gap being provided between said floor and the rear wall of the casing, the side walls of said casing having guideways therein adapted to receive the shaft of a bolt of toweling, the loose web of the towel depending through said gap in the rear of said floor and being drawn forward by the user through said opening, said guideways being positioned to direct the bolt of toweling by

gravity against said floor, the frictional contact of said bolt with said floor retarding the unwinding of said bolt and preventing too rapid feed of the towel, and said casing having a soiled towel compartment below said opening wherein the towel falls when released by the user.

3. A towel cabinet comprising a casing having a delivery opening in its upper portion at the front of the cabinet, a transverse floor within said casing in the rear of said opening, a comparatively narrow gap being provided between said floor and the rear wall of the casing, the side walls of said casing having guideways therein adapted to receive the shaft of a bolt of toweling, the loose web of the towel depending through said gap in the rear of said floor and being drawn forward by the user through said opening, said guideways being positioned to direct the bolt of toweling by gravity against said floor, the frictional contact of said bolt with said floor retarding the unwinding of said bolt and preventing too rapid feed of the towel, and said casing having a soiled towel compartment below said opening wherein the towel falls when released by the user.

In witness whereof, I have hereunto set my hand this 7th day of February, 1921.

GEORGE A. STEINER.
